UNITED STATES PATENT OFFICE.

RUSSELL B. KINGMAN, OF ORANGE, NEW JERSEY, ASSIGNOR TO THE CHORE UTENSILS CORPORATION OF AMERICA, OF ORANGE, NEW JERSEY, A CORPORATION OF NEW JERSEY.

SCOURING DEVICE.

Application filed November 17, 1922. Serial No. 601,477.

To all whom it may concern:

Be it known that I, RUSSELL B. KINGMAN, a citizen of the United States of America, and a resident of Orange, county of Essex, 5 State of New Jersey, have invented certain new and useful Improvements in Scouring Devices, of which the following is a specification.

This invention relates to scouring devices, 10 and more particularly to devices of this kind used for cleaning or scouring pots and pans or the like. Such devices are commonly made in the form of gloves fitting over the hand of the user, and the fabric of the 15 gloves is composed of spaced threads, the threads running in one direction being surrounded entirely or partly by thin strands of sheet metal, say copper. These threads, for reasons of effectiveness during use of 20 the article, are spaced relatively far apart, and consequently the finger-tips of the person using such glove will come in contact with the object to be scoured, through the loose meshes of the fabric and are thus 25 liable to be soiled. Moreover, gloves have the disadvantage that they are made to surround the whole hand, while, as a matter of fact, only a very small portion of the glove 30 will be used, viz, that portion which lies between the finger-tips and the object to be scoured.

It is the purpose of the present invention to overcome these drawbacks, and I have attained this object by devising an article 35 in which a sufficient thickness of material and preferably several layers of fabric are interposed between the finger tips of the person using it and the object to be scoured, and in which the space for the insertion of 40 the fingers is just sufficient for the purpose to be accomplished. These objects and the advantages of my invention will appear fully from the description following hereinafter, and the novel features will be pointed out in the appended claims.

Without desiring to restrict myself to the details shown, I have illustrated in the accompanying drawings a preferred embodiment of my invention. In these drawings, 50 Fig. 1 is a rectangular piece of fabric from which the device is constructed; Figs. 2 and 3 illustrate successive steps in the construction of a preferred form thereof; Fig. 4 is a diagrammatic section on the line 4—4 of Fig. 3 and Figs. 5 and 6 are face views

showing inner and outer layers of the completed device when made as in the illustrated example.

The material from which the device is constructed comprises spaced cotton threads 60 10 running in one direction and spaced metal-containing threads 11 running in a transverse direction, said threads 10 and 11 being woven together to form a relatively open weave or open mesh fabric. The metal 65 may be combined with the threads 11 in any convenient manner as for instance by spirally winding strips of metal about the same as shown; in some cases the threads 11 may be composed entirely of metal. 70

When completed, the device comprises what may be termed a pocket of such size as to accommodate the fingers of the user, but of less depth than the distance between the finger-tips and the knuckles on the back of 75 the hand. The device is preferably of tapering form, that is with the side edges converging toward one end and is of sufficient textural density to prevent contact between the fingers and the object to be scoured; thus 80 as shown the device may be of triangular shape, it being understood however that this is only representative of equivalent forms.

When constructed, as in the illustrated example, a rectangular piece of the fabric, 85 such as shown, for instance in Fig. 1, is folded along a diagonal 12 of the rectangle, into the triangle 13 shown in Fig. 2. This triangular folded fabric is then folded upon itself on the line 14 to form another triangle 15 of half the size of the first triangle, as shown in Fig. 3. One set of contacting edges, for instance the edges 16, are then sewed or otherwise secured together, while the connecting edges 17 are left free 95 and open to permit the fingers to be inserted into the resulting pocket 18. With the described arrangement the device consists of two sets of double layers of fabric *a* and *b* lying one within the other to form a two-ply device; it will be noted that the metal-containing threads 11 in one layer or ply run transversely and at approximately right angles to the corresponding threads of the contiguous layer as shown in Figs. 5 and 6. 105 This arrangement not only gives the desired textural density but also disposes the threads, and more particularly the metal-containing threads 11, in the most efficient relation.

It will, of course, be understood that, if 110

desired, the number of layers of material included in the pocket may be other than as shown in the illustrated example. The device is particularly useful for scouring pots, 5 pans and the like and by fitting over the finger-ends alone insures a freedom of action and flexibility which enables the user to reach all parts of the article being scoured, with a minimum of effort, so that 10 the scouring action is positive and efficient.

Various changes in the specific form illustrated and described may be made within the scope of the claims without departing from the spirit of the invention.

15 I claim:

1. A scouring device composed of metal-containing fabric comprising outer layers of such fabric of sufficient combined textural density to prevent contact between the 20 fingers and the object to be scoured, a pocket between said fabric layers to accommodate the fingers of the user but of less depth than the distance between fingers tips and the knuckles.

25 2. A scouring device of triangular shape consisting of two sets of double layers of metal-containing fabric, said layers being connected along two edges, and open along one edge for the insertion of the user's fin-

gers between adjacent layers of the two sets.

3. A scouring device made by folding a rectangular piece of metal-containing fabric first along a diagonal of the rectangle into triangular shape, then folding the resulting triangle to form another triangle of half the size of the first triangle, and then sewing one set of contacting edges together, but leaving the other set of edges open to form a pocket for the insertion of the user's 35 fingers.

4. A scouring device made of a rectangular piece of fabric having spaced metal-containing threads in one direction and spaced cotton threads in the other direction, said 45 piece of fabric being folded into a plurality of layers in such a way that the metal-covered threads of an outer layer and those of the adjacent inner layer cross each other, said layers being connected along a plurality 50 of edges and disconnected along another edge to provide a pocket adjacent to said second-named layer for the insertion of the user's fingers.

In testimony whereof I have hereunto set 55 my hand.

RUSSELL B. KINGMAN.
